UNITED STATES PATENT OFFICE.

ANTONI BRZYKCY, OF MINNEAPOLIS, MINNESOTA.

WINDMILL.

1,241,918.

Specification of Letters Patent.

Patented Oct. 2, 1917.

Application filed November 9, 1916. Serial No. 130,822.

To all whom it may concern:

Be it known that I, ANTONI BRZYKCY, a citizen of the United States, residing at Minneapolis, in the county of Hennepin and State of Minnesota, have invented certain new and useful Improvements in Windmills; and I do hereby declare the following to be a full, clear, and exact description of the invention, such as will enable others skilled in the art to which it appertains to make and use the same.

My invention relates to improvements in windmills; and to this end, it consists of the novel devices and combinations of devices hereinafter described and defined in the claims.

In the accompanying drawings, which illustrate the invention, like characters indicate like parts throughout the several views.

Referring to the drawings,

Figure 1 is a side elevation of the improved windmill with some parts broken away and some parts shown in different positions by means of broken lines;

Fig. 2 is a vertical section taken on the line 2—2 of Fig. 1;

Fig. 3 is a detail view, principally in horizontal section taken on the line 3—3 of Fig. 1, on an enlarged scale; and

Fig. 4 is a detail view, partly in plan and partly in horizontal section taken on the line 4—4 of Fig. 1.

The numeral 1 indicates the tower of a windmill which, as shown, is of the usual construction and has at its top a turntable 2. Mounted on this turntable 2, is a head 3 comprising upper and lower disks 4 connected by a bushing 5, which extends axially therethrough. The lower end of the bushing 5 is extended axially through the turntable 2 and journals the head 3 thereto for horizontal rotary movement. Anti-friction bearings 6 are interposed between the turntable 2 and head 3.

The vane of the windmill is indicated by the numeral 7 and its shank 8, as shown, comprises a pair of channel bars placed back to back and rigidly connected by rivets. The inner end of the shank 8 is inserted between the disks 4 of the head 3 and the members thereof bent outward to embrace the bushing 5 of said head. These members of the shank 8 are tightly clamped onto the bushing 5, to secure the head 3 for common horizontal swinging movement with the vane 7. The flanges of the shank 8 are also riv-

eted to the disk 4 of the head 3 to more securely connect the several members of said head and shank.

A relatively large segmental gear 9 rests directly on the head 3 and the upper end of the bushing 5 extends axially part way into the hub thereof, with freedom for rotation therein. An oscillatory tubular shaft 10 is extended through the bushing 5 and segmental gear 9 and which gear is secured thereto, for common oscillatory movement, by a set screw 11. The upper end of the shaft 10 is extended above the hub of the gear 9 and has rigidly secured thereto a bearing bracket 12, and the lower end of said shaft is journaled in a bearing bracket 13 rigidly secured, although not shown, to the tower 1.

The wind-wheel 14 may be of the usual or any suitable construction and its shaft 15 is journaled in the bearing bracket 12, directly above the tubular shaft 10 and at right angles thereto. A power shaft 16 is extended through the tubular shaft 10 and has on its upper end a gear 17, which meshes with a pinion 18 on the shaft 15 of the wind-wheel. On the lower end of the power shaft 16, is a gear 19, which meshes with a gear 20 on a horizontal shaft 21, having a belt pulley 22.

From the above description, it is evident that the wind-wheel 14 is free to swing in a horizontal plane, with respect to the vane 7, and a pair of circumferentially spaced pins 23, projecting radially from the upper disk of the head 3, are alternately engaged by a depending pin 24 on the segmental gear 9, to limit the swinging movement of the wind-wheel 14 from a position "in the wind" or at right angles to the vane 7 to a position "out of the wind" or substantially parallel with said vane.

A lock pin 25 is provided for rigidly connecting the segmental gear 9 to the head 3 in either of its extreme positions. This lock pin 25 is mounted in a bore or seat 26 in the upper disk of the head 3 and its upper end is arranged to alternately enter a pair of circumferentially spaced apertures 27 in the lower face of the segmental gear 9 and thereby lock said head and gear for common oscillatory movement. Endwise movement is imparted to the lock pin 25 by a lever 28, intermediately fulcrumed at 29 to the shank 8 and has its short end pivotally connected to the lower end of said lock

pin. On the long end of the lever 28, is a weight 30 which holds the upper end of the lock pin 25 in direct contact with the lower face of the segmental gear 9, while said gear is moving from one extreme position to the other, and also moves said lock pin 25 into the apertures 27.

The following connections are provided for moving the wind-wheel 14 from one extreme position to the other, with respect to the vane 7, to wit:—A countershaft 31 is journaled in a bearing bracket 32 rigidly secured to the shank 8 and has on its inner end a pinion 33, which meshes with the segmental gear 9. On the outer end of the countershaft 31, is a sprocket wheel 34, over which runs a short length of sprocket chains 35, having attached to its depending ends a pair of pulling cables 36.

20 The lock pin 25 is released from the segmental gear 9 by a cable 37 attached, at one end, to the weight 30 and having its intermediate portion passed over a guide sheave 38 on the countershaft 31. The lower ends 25 of the cables 36 and 37 are of sufficient length to permit the same to be easily reached by an operator standing on the ground. To move the wind-wheel 14 into or out of the wind, the segmental gear 9 is released from the head on the shank 8 by drawing on the cable 37 to lift the weight 30, and hence, the lever 28 to withdraw the lock pin 25 from the engaged aperture 27. Then by drawing on one of the cables 36, 35 depending whether the wind-wheel is to be moved into or out of the wind, the segmental gear 9 is oscillated on the head 3 through the several connections, previously described.

40 The bearing bracket 12, gears 17 and 18 are so designed, as to bring the wind-wheel 14 very close to the axis of the head 3, which is very desirable, in order to make the movement of the wind-wheel 14 to and from a 45 position in the wind easier. The power developed by the wind-wheel 14 may be used for various different purposes by applying a belt, not shown, to the pulley 22.

What I claim is:—

50 1. In a windmill, a turntable, a vane having on the inner end of its shank a head rotatively mounted on the turntable, a gear mounted on the head for oscillatory movement, a bearing bracket secured to the gear for oscillatory movement in a horizontal plane above the head, a wind-wheel journaled on the bearing bracket, a power shaft 55 extending axially through the turntable, head and gear, driving connections between the wind-wheel and power shaft, means for locking the gear directly to the head in either of its extreme oscillated positions, and means, including a pinion meshing with the

gear, for oscillating said gear from one extreme position to the other.

65 2. In a windmill, a turntable, a vane having on the inner end of its shank a head rotatively mounted on the turntable, a gear mounted on the head for oscillatory movement, a bearing bracket secured to the gear, 70 a wind-wheel journaled on the bearing bracket, a power shaft extending axially through the turntable, head and gear, driving connections between the wind-wheel and power shaft, a weighted lever having a lock pin 75 mounted in the head and arranged to alternately enter a pair of circumferentially spaced apertures in the gear to lock said gear to the head in either of its extreme oscillated positions, means for actuating said lever to release its lock pin, and means, 80 including a pinion meshing with the gear, for oscillating said gear from one extreme position to the other.

85 3. In a windmill, a turntable, a vane having on the inner end of its shank a head rotatively mounted on the turntable, a gear mounted on the head for oscillatory movement, a bearing bracket secured to the gear for oscillatory movement in a horizontal 90 plane above the head, a wind-wheel journaled on the bearing bracket, a power shaft extending axially through the turntable, head and gear, driving connections between the wind-wheel and power shaft, means for locking the gear to the head in either of its extreme oscillated positions, a countershaft journaled on the shank of the vane, a pinion 95 on the countershaft and meshing with the gear, and means for oscillating the counter-shaft, at will.

100 4. In a windmill, a turntable, a vane having on the inner end of its shank a head rotatively mounted on the turntable, a gear mounted on the head for oscillatory movement, a bearing bracket secured to the gear for oscillatory movement in a horizontal plane above the head, a wind-wheel journaled on the bearing bracket, a power shaft 105 extending axially through the turntable, head and gear, driving connections between the wind-wheel and power shaft, means for locking the gear to the head in either of its extreme oscillated positions, a countershaft journaled on the shank of the vane, a pinion 110 on the countershaft and meshing with the gear, a sprocket wheel on the countershaft, and a sprocket chain arranged to run over the sprocket wheel for oscillating the countershaft.

115 120 In testimony wherof I affix my signature in presence of two witnesses.

ANTONI BRZYKCY.
